BRAKE MECHANISM FOR WELL
MACHINERY

Asa Judson Neff, Laredo, Tex.

Application January 23, 1936, Serial No. 60,498

9 Claims. (Cl. 188—77)

This invention relates to means for controlling the brake of well machinery such as draw works drilling machines.

An object is to provide a brake of simple construction which is adjustable to produce the desired braking effect for every condition of drilling and for raising and lowering the drill pipe or setting the casing.

Another object is to enable the operator to make adjustments quickly to meet any conditions and at the same time relieve him from the necessity of weighting or tying the brake lever to hold the brake properly while the machine is in operation.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a front elevation of a portion of a well machine having the present improvements, portions being broken away.

Figure 2 is an end view thereof partly in section and partly in elevation.

Figure 3 is a plan view with parts broken away.

Figure 4 is a side elevation of the brake applying and locking mechanism, shown in released position by full lines and in applied, locked position by broken lines, the brake lever being broken away.

Figure 5 is a transverse section through one of the bearings of the brake mechanism and showing said mechanism in elevation.

Figure 6 is a side elevation of the brake adjusting mechanism.

Figure 7 is a front elevation thereof.

Referring to the figures by characters of reference, 1 designates the frame of the well machinery on which are mounted the usual brake drums 2 the periphery of each of which is engaged by a brake band 3. Lugs 4 can be connected to the bands at one end for engagement by adjustable connecting rods 5 pivoted to the ends of a centrally fulcrumed equalizing lever 6.

Fixedly secured to the frame 1 are spaced bearings 7 in each of which is located a cylindrical bushing 8 having a radial arm 9. An eccentric

bore 10 is provided in each bushing and these bores receive a shaft 11.

Mounted on shaft 11 so as to rotate therewith are arms 12 and 13 arranged in pairs, each pair being coupled to one of the bands 3 at that end remote from the lug 4. Thus when the shaft 11 is rotated in one direction the arms 12 and 13 will pull on the bands 3 so as to tighten them about brake drums 2, the pressure of the two bands being equalized by lever 6.

One of the arms 12 has an extension 14 joined by a link 15 to an arm 16 extending radially from a brake operating shaft 17. A hand lever 18 is utilized for rocking shaft 17 and during such movement the arm 16 and link 15 act as a toggle 15 for transmitting motion to extension 14, arms 12 and shaft 11, thereby to apply or release the brake.

The axial center of the point of connection between arm 16 and link 15 has been indicated at *a* and the axial center of the point of connection between link 15 and extension 14 has been indicated at *b*. The axial center of shaft 17 is shown at *c*.

When the brake is to be applied, the lever 18 is moved from full-line to broken line position 25 in Figure 4. This causes the arm 16 to press through link 15 against extension 14, causing the shaft 11 to rotate in one direction and apply the brake bands to the drums. When the point of extreme application is reached the centers *c*, *a* 30 and *b* have assumed the positions indicated at *c*, *a'* and *b'* where they are either on a dead center or slightly past the dead center, being limited by a suitably disposed stop 19 engaged by lever 18 or some other part of the mechanism. 35 Thus the brake will be held in applied position and it is not necessary to weight or tie down the lever 18 in order to relieve the operator.

Should it be desired to reduce or increase the slack in bands 3 so that their maximum pressure 40 upon the drums will be either increased or reduced to meet the working requirements, the two bushings 8 can be simultaneously rocked to advance shaft 11 toward or retract it from the brake drums. This operation is effected by means of 45 an adjusting shaft 20 having radial arms 21 connected by links 22 to the arms 9 on the bushings. An adjusting lever 23 is secured to shaft 20 and by means thereof the shaft can be rocked to adjust the bushings annularly and effect the 50 desired advance or retraction of the shaft 11. Any suitable means such as a dog 24 and a toothed segment 25, can be employed for holding the lever 23 and associated parts in any positions to which they may be adjusted.

It will be apparent from the foregoing that the frictional engagement of the brake bands with the drums can be quickly and easily increased at the will of the operator at any time simply by shifting lever 23 and no matter to what position this lever may be moved, the toggle formed by arm 16 and link 15 will always be brought to or slightly past dead center position when the lever 18 is given its maximum movement in one direction. Consequently the brake will be held or locked in full applied position following any adjustment thereof.

By providing a brake which can be quickly and easily adjusted, and which will be held when applied as described, it will meet any requirements such as lowering or lifting a drill pipe, setting a well casing, etc.

What is claimed is:

1. In a brake mechanism a brake drum, a band, 20 a rocker shaft, means operated by said shaft for shifting said band relative to the drum, positively controlled adjusting means operable by the user for changing the position of the shaft by advancing or retracting the shaft bodily relative to 25 the drum to increase or reduce the slack in the band, and means for rocking the shaft and locking it in one extreme position independently of said bodily movement of the shaft, thereby to tighten and hold the band, said shaft advancing 30 means operating independently of the action of the shaft rocking means.

2. In a brake mechanism a brake drum, a band, a rocker shaft, means operated by said shaft for shifting said band relative to the drum, means for 35 rotating the shaft in one direction to apply the band to the drum and to hold the shaft against retrograde rotation when brought to one extreme position, and positively controlled means operable by the user for changing the position of the 40 shaft by advancing and retracting the shaft bodily relative to the drum and independently of the action of the shaft rotating means, to vary the pressure of the band upon the drum when the shaft is held in said extreme position.

45 3. In a brake mechanism a brake drum, a band, a rocker shaft, means operated by said shaft for shifting said band relative to the drum, toggle means shiftable to or past a dead center for adjusting the shaft annularly in one direction to 50 apply the band to the drum and to hold the shaft against retrograde movement when brought to one extreme position, and means for advancing and retracting the shaft relative to the drum to vary the pressure of the band upon the drum 55 when the shaft is held in said extreme position.

4. In a brake mechanism a brake drum, a band, a rocker shaft, means operated by said shaft for shifting said band relative to the drum, toggle means shiftable to or past a dead center for 60 adjusting the shaft annularly in one direction to apply the band to the drum and to hold the shaft against retrograde movement when brought to one extreme position, means for limiting the movement of the toggle means when in holding 65 position, and means for advancing and retracting the shaft relative to the drum to vary the pressure of the band upon the drum while the toggle means is held by its limiting means.

5. In a brake mechanism a brake drum, a band, 70 a rocker shaft, means operated by said shaft for

shifting said band relative to the drum, toggle means shiftable to or past a dead center for adjusting the shaft annularly in one direction to apply the band to the drum and to hold the shaft against retrograde movement when brought to one extreme position, an eccentric bearing for the shaft and means for adjusting the bearing annularly to advance or retract the shaft relative to the drum to vary the pressure of the band upon the drum while the shaft is held in said extreme 10 position.

6. In a brake mechanism a brake drum, a band, a rocker shaft, means operated by said shaft for shifting said band relative to the drum, toggle means shiftable to or past a dead center for 15 adjusting the shaft annularly in one direction to apply the band to the drum and to hold the shaft against retrograde movement when brought to one extreme position, an eccentric bearing for the shaft, means for adjusting the bearing annularly to advance or retract the shaft relative to the drum to vary the pressure of the band upon the drum while the shaft is held in said extreme 20 position, and means for holding the bearing against movement away from adjusted position. 25

7. A brake mechanism including cooperating rotatable and anchored brake elements, a rocker shaft, means operated by said shaft for shifting the anchored brake element, a toggle for rotating the shaft to shift the anchored brake element, 30 means for actuating the toggle to or past a dead center to hold the shaft and the shifted brake element against retrograde movement, limiting means for the toggle, and means for shifting the shaft toward or from the rotatable brake element without disturbing the relative positions of the toggle, its operating means and the shaft. 35

8. A brake mechanism including cooperating rotatable and anchored brake elements, a rocker shaft, means operated by said shaft for shifting 40 the anchored brake element, means for rotating the shaft in one direction to apply the anchored brake element to the rotatable brake element and to hold the shaft against retrograde movement when brought to one extreme position, and 45 positively controlled means operable by the user for changing the position of the shaft by advancing or retracting the shaft bodily relative to the rotatable element and independently of the action of the shaft rotating means, to vary the 50 braking pressure of the anchored element when the shaft is held in said extreme position.

9. A brake mechanism including cooperating rotatable and anchored brake elements, a rocker shaft, means operated by said shaft for shifting 55 the anchored brake element, means for adjusting the shaft annularly in one direction to apply the anchored brake element to the rotatable brake element and to hold the shaft against retrograde movement when brought to one extreme position, 60 and means for advancing or retracting the shaft relative to the rotatable element to vary the braking pressure of the anchored element when the shaft is held in said extreme position, said means including a rotatable bushing, means for actuating the bushing, and means for holding the bushing against rotation, said bushing having an 65 eccentric bearing for the shaft.
